UNITED STATES PATENT OFFICE.

HENRY ALEXANDER MILLAR, OF BUENOS AYRES, ARGENTINA.

FEED-WATER HEATER.

SPECIFICATION forming part of Letters Patent No. 628,344, dated July 4, 1899.

Application filed January 17, 1899. Serial No. 702,443. (No model.)

To all whom it may concern:

Be it known that I, HENRY ALEXANDER MILLAR, a subject of the Queen of Great Britain, residing at Buenos Ayres, Argentina, 5 have invented a new and useful Improvement in Boilers, of which the following is a full, clear, and exact description.

The object of the invention is to provide certain new and useful improvements in boilers, whereby the feed-water heater forms a deflecting-arch for deflecting the heat arising from the burning fuel to the front of the fire-box and at the same time highly heating the feed-water and causing a circulation of the 15 water in the boiler through the feed-water device.

The invention consists of novel features and parts and combinations of the same, as will be fully described hereinafter and then pointed 20 out in the claims.

A practical embodiment of my invention is represented in the accompanying drawings, forming a part of this specification, in which similar characters of reference indicate corresponding parts in all the views.

Figure 1 is a longitudinal sectional elevation of the improvement as applied to a locomotive-boiler, the section being on the line 1 1 in. Fig. 2. Fig. 2 is an inverted sectional 30 plan view of the same on the line 2 2 in Fig. 1, and Fig. 3 is an enlarged transverse section of the same on the line 3 3 in Fig. 1.

A is the fire-box, B its exterior shell, and C is part of the barrel of the boiler.

The feed-water heater consists of two tubular receptacles D D', closed at the ends and connected by two rows of tubes d. It is supported upon studs a, projecting from the sides and back of the fire-box, or on water-tubes b, 40 running from front to back of the fire-box in an inclined position corresponding with that usually occupied by the fire-brick deflecting-arch.

A pipe E, which passes through the water-space behind the fire-box to the receptacle D, has a branch E' bent outward and upward to a valve-box e, where there is a valve governing a communication with the barrel of the boiler. Within the pipe E is another pipe F, 50 also opening into the receptacle D, and having a branch F' passing outward and upward to a valve-box f, where there is a valve gov-

erning a communication with the barrel of the boiler. The feed-pump G, which is supplied, as usual, by the pipe g from the tender or 55 tanks, has its discharge connected by a pipe H to the box h, which communicates with f and contains a check-valve. From the receptacle D' two pipes d' d' lead up through the crown of the fire-box to the water-space 60 above.

Instead of or in addition to the feed-pump G an injector may be employed communicating with the box h.

The apparatus operates as follows: The 65 valves in e and f being closed, the feed-water from the pump or injector, having passed the check-valve in h, flows by the branch F' and pipe F into the receptacle D, thence through the tubes d to D', and thence up the pipes d' 70 d' into the boiler, being heated on its way. The valves in e and f being open, water can also pass from the barrel of the boiler through the heater to the space above the fire-box, so that thus there is a circulation of water 75 through the heater. The circulation can go on whether the pump or injector is or is not at work.

Two rows of tubes d are shown in the drawings, those of the upper row being over the 80 spaces between those of the lower row, so as the better to obstruct passage of flame or gases directly upward. There might obviously be more than two rows of tubes d, and over these tubes there might be placed a baffle- 85 plate to prevent any passage of flame or gases between the tubes.

K is a blow-off pipe, having in a convenient position a cock which can be opened to blow out deposit. The receptacles D D' are also 90 provided with screw-plugs k, which can be unscrewed when it is desired to wash out the heater.

Having thus described the nature of this invention and the best means I know for carrying the same into practical effect, I claim—

1. The combination, with a boiler having a fire-box and a boiler-shell, of two tubular receptacles disposed transversely in the fire-box, pipes extending between and engaging 100 the receptacles with each other, a pipe leading from one receptacle upward to the boiler-shell, a pipe communicating with the other receptacle and passing without the boiler and

having a branch extending upward at the outside of the boiler, a box with which said branch communicates, the box in turn communicating with the boiler-shell, an additional pipe extending through the pipe that is connected with the said other receptacle, the additional pipe passing out of the pipe in which it is contained upward to the side of the boiler-shell opposite the said branch pipe, a second box in communication with the said additional pipe and communicating with the boiler-shell, a pump, and a pipe extending between the pipe and one of the said boxes.

2. The combination, with a boiler having a fire-box and a boiler-shell, of a feed-water-heating receptacle mounted in the fire-box, a pipe leading from said receptacle to the water-space of the boiler, a second pipe leading from the receptacle to a point without the boiler, a branch communicating with the second pipe and extending upward at one side of the boiler, a box with which said branch communicates, the box having communication with the water-space of the boiler, an additional pipe extending through said second pipe and projecting out of the same and upward at the side of the boiler opposite the

said branch pipe, a box with which the said additional pipe communicates, the box having communication with the water-space of the boiler, a pump, and a pipe connecting the pump with one of the boxes.

3. In a feed-water-heating apparatus, the combination with a boiler, of a feed-water-heating receptacle mounted in the fire-box, a pipe in the fire-box and serving to connect the said receptacle with the steam-space of the boiler, a second pipe communicating with the heating-receptacle and passing outside of the boiler and having a branch leading upward to and communicating with the boiler, and a third pipe situated within the second pipe and communicating with the heating-receptacle, the third pipe having a branch passing out of the second pipe and leading upward to and communicating with the opposite side of the boiler.

In testimony whereof I have hereunto set my hand in the presence of two subscribing witnesses.

HENRY ALEXANDER MILLAR.
